UNITED STATES PATENT OFFICE.

BENJAMIN WATTS MORGAN, OF TAMPA, FLORIDA, ASSIGNOR TO SIMPLEX PRESS COMPANY, OF ATLANTA, GEORGIA, A CORPORATION OF GEORGIA.

PRINTING-PRESS.

No. 853,590.

Specification of Letters Patent.

Patented May 14, 1907.

Application filed April 15, 1903. Renewed June 7, 1906. Serial No. 320,606.

To all whom it may concern:

Be it known that I, BENJAMIN WATTS MORGAN, a citizen of the United States, residing at Tampa, in the county of Hillsboro 5 and State of Florida, have invented a new and useful Printing-Press, of which the following is a specification.

This invention relates to improvements in printing presses, more particularly that class 10 employing a reciprocatory bed and a revolute cylinder located thereover. The various features of the invention may, however, be employed upon different forms of presses as, for instance, the double cylinder type. 15 These changes will be readily understood by those skilled in the art when the nature of the invention is apprehended.

It is the primary object of this invention to provide a structure that is extremely simple 20 in its make-up, the successive action of the various parts being controlled by a single element, which, in turn, is actuated by the bed.

More particularly the invention relates to novel means for moving said bed, elevating 25 the cylinder during the retrograde movement thereof, simultaneously actuating the paper gage, and also throwing the fly-frame.

The preferred embodiment of the invention is illustrated in the accompanying drawings, wherein:

Figure 1 is a side elevation of the press. Fig. 2 is a longitudinal sectional view through the same. Fig. 3 is a transverse sectional view. Fig. 4 is a section taken on the line 35 $x-x$ of Fig. 3. Fig. 5 is a detail sectional view through the guides. Fig. 6 is a detail section through one of the pulleys of the fly-frame. Fig. 7 is a horizontal sectional view 40 through a portion of the structure. Fig. 8 is a detail sectional view through a portion of the bed and cushion.

Similar reference numerals indicate corresponding parts in all the figures of the drawings.

In the embodiment illustrated, a supporting frame 10 is employed, which may be of any suitable construction, having intermediate standards 11, projecting above its upper edge, and longitudinally disposed tracks 12 45 on its opposing inner faces. Arranged within this frame is a reciprocatory bed 13 having spaced depending flanges 14 at its side edges, constituting tracks upon which the hubs 15 of bearing rollers 16 rest, said rollers running

upon the tracks 12 of the frame and having 55 their upper portions disposed between the flanges. Pins 16^a are located at the ends of the flanges 14 and are arranged to be engaged by the journals of the rollers, whereby said rollers are kept in true position. The bed is 60 constructed to receive on its upper face a suitable form 17 and at its front end is located a cushion 18, that has side extensions, as shown at 19. As shown in Fig. 8, the cushion comprises simply a metallic block 65 having a compressible pad thereon and adjustably secured to the bed by slot and bolt connections 19^a. This cushion should not be confused with the rails that hold the forms in place upon the bed. They are for an entirely 70 different purpose as hereinafter pointed out.

The means for moving the bed is in the form of an endless belt or chain 20, passing around a pair of sprocket wheels 21, that are located centrally of the frame, one of these 75 wheels being secured to the inner end of a drive shaft 22, having on its outer end a suitable fly-wheel 23. The other sprocket wheel is journaled upon a stud 24, that is longitudinally adjustable in a slot 25 formed 80 in the frame. The chain is connected to the bed by means of a link 26 pivoted at one end to said chain, the other end having a longitudinal slot 27 in which a stud 28 engages, said stud being carried by a lug 29 depending 85 from the central web of the bed. It will thus be seen that, as the chain is moved through the medium of the drive shaft, the link connection will cause the bed to travel in the direction of the movement of the upper stretch of the belt 90 or chain. When the link approaches one of the sprocket wheels in passing around said wheel, the points of connection of said link will approach each other but, as the link can freely slide upon the stud 28, it is permitted 95 to pass about the wheel without interference, whereupon it assumes its original relation and the bed is moved in an opposite direction.

The cylinder is designated by the reference numeral 30, and is movable toward and from 100 the bed. For this purpose a suspending frame is employed comprising a hanger bar 31, vertically slidable in slots 32 formed in the standards 11. This bar is provided just inside the standards with enlargements 33 having vertical openings through which pass hanger arms 34. The upper ends of the hanger arms are threaded and upon the same are

screwed holding-nuts 35 that bear against the enlargements 33 and hold the hanger arms against movement therethrough, though said arms may be readily adjustable by manipulating the nuts. The arms, and consequently the hanger bar 31, are held against swinging movement by suitable studs 36, arranged on the inner face of the standards 11 and embracing the arms, as illustrated in Fig. 10 2. The lower ends of the arms are provided with suitable journals 37, in which are mounted the gudgeons 38 of the cylinder 30. Levers 39 are pivoted between their ends, as shown at 40, to the outer sides of the standards 11, said levers having enlarged upper ends 41 which are provided with cam slots 42, in which the projecting ends of the hanger bar 31 engage. The lower ends of these levers are connected by links 43 with a yoke slidably 15 mounted on the supporting frame. This yoke consists of longitudinally movable side bars 44 arranged in suitable guide-ways 45 of the frame, and connected at their ends by head pieces 46 extending across the ends of 20 the machine in the path of movement of the bed. In order to prevent injurious contact between the bed and the heads 46, spring buffers 47 are preferably carried by said heads and arranged on the sides thereof, so 25 that they will be struck by the ends of the bed.

The feed table of the press is shown at 48 and declines to a position contiguous to the cylinder. Located contiguous to the lower end of the table is a transverse rod 49, carrying upwardly projecting gage stops 50, that are normally located below the plane of the table. The rod 49 is attached to the cylinder bars 34 by means of links 51 which rest upon inwardly projecting pins 52 that are carried 30 by the standards. It will thus be seen that, when the cylinder is elevated, the gage stops will also be raised above the plane of the table and when said cylinder is dropped, the stops will be depressed below the plane of the 35 table. At the same time, during this movement, the links 51 will rock slightly upon the pins 52 and as a result, when the gage is in its lowermost position, the stops thereof will be spaced from the cylinder, but when elevated, 40 will be in engagement with the same.

For the purpose of properly directing the paper beneath the cylinder, suitable guides are employed. Rods 53 extend across the frame on opposite sides of the lower portion 55 of the cylinder, and metallic or other strips or tapes 54 extend from the lower edge of the table, beneath the cylinder, and to the rod on the opposite side of the same. These metallic strips are thus interposed between the 60 cylinder and the bed, and are arranged directly over the longitudinal bars of the chase, as illustrated in Fig. 3. The ends of the metallic strips are bifurcated, to permit the placing of small pulleys 55 upon the supporting 65 rods 53. Around these pulleys are passed

endless tapes 56 that, therefore, have their stretches arranged on opposite sides of the metallic strips and beneath the cylinder. In practice, either the metallic strips or endless tapes may be dispensed with, or the two may 70 be employed together, as illustrated, in which case the upper portions of the tapes are supported by and upon the metallic strips.

In the structure herein illustrated, an oscillating fly-frame is employed, said frame consisting of a rock-shaft 57 carrying suitable fingers 58 that project toward the cylinder. The ends of the shaft 57 carry rigidly attached pulleys 59, and upon these pulleys are wrapped cords or cables 60. The ends 80 of the cables are fastened at separated points to the yoke. The inking apparatus may be of any desirable construction, but has not been shown in order to avoid confusion.

The operation of the machine is substantially as follows: Assuming the bed beneath the feed table, a sheet in position against the gages, and the drive shaft in operation by any suitable means, it will be apparent that the bed will be moved under the cylinder 85 (which is in its lowered position). The cushions 18 will first pass beneath said cylinder, slightly raise the same and put it in position in advance of the forms. This will cause the sheet of paper to be gripped between the 90 cylinder and tapes some distance in advance of the line of impression and thus the paper will be drawn into proper position to register on the type forms. By adjusting the cushions, either forward or back, the register may 95 be changed. The bed, moving onwardly, will traverse the frame to the opposite end of the same. Here the end of the bed will contact with the buffer 47, consequently moving the yoke longitudinally of the machine. This movement will cause the levers 100 105 110 115 120 125 130 135 140 145 150 155 160 165 170 175 180 185 190 195 200 205 210 215 220 225 230 235 240 245 250 255 260 265 270 275 280 285 290 295 300 their operative positions. It will be apparent that this machine is very simple in its structure, the various members being actuated from the single yoke, which, in turn, is moved by the bed. The mechanism for actuating the bed is also very simple and the mounting of one of the sprocket wheels permits any slack in the chain being taken up, or the shortening of the chain, if less movement is required on the part of the press bed. The various elements are of such structure that they will not readily become deranged, and yet, should they from any cause need repair, access may be had to them for this purpose.

From the foregoing, it is thought that the construction, operation, and many advantages of the herein described invention will be apparent to those skilled in the art, without further description, and it will be understood that various changes in the size, shape, proportion, and minor details of construction may be resorted to without departing from the spirit, or sacrificing any of the advantages of the invention.

Having thus described my invention what I claim as new and desire to secure by Letters Patent is:

1. In a printing press, the combination with a hanger, of a cylinder suspended from and located beneath the hanger, separate devices, each engaged with one end of the hanger above the cylinder for effecting the raising and lowering of the cylinder, and a bed coacting with the cylinder.

2. In a press, the combination with a frame, of a transversely disposed vertically movable hanger bar mounted on the frame, hanger arms suspended from and beneath the bar, a cylinder journaled on the arms, means for elevating the bar and a bed coacting with the cylinder.

3. In a press, the combination with a frame, of a vertically movable hanger bar mounted thereon, hanger arms adjustably mounted on the bar, a cylinder journaled on the arms and a bed coacting with the cylinder.

4. In a press, the combination with a frame, of a hanger bar mounted thereon having openings therethrough, hanger arms having their upper ends passed through the openings, nuts threaded on said ends, a cylinder journaled in the lower ends of the arms and a bed coacting with the cylinder.

5. In a press, the combination with a bed, of swinging levers located on opposite sides of the bed and having cam surfaces at their upper ends, said surfaces being disposed above the horizontal plane of the bed, a hanger frame having at its upper portion devices which engage the cam surfaces, a cylinder suspended in the frame and coacting with the bed, and means actuated by the bed for effecting the movement of the levers.

6. In a press, the combination with a bed, of a cylinder, means for elevating the cylinder, said means including a swinging lever having a connection with the cylinder, an actuating bar located longitudinally of the bed, and a connection between the bar and lever.

7. In a press, the combination with a bed, of a cylinder, means for elevating the cylinder, said means including a swinging lever having a cam connection at its upper end, and actuating means having a connection with the lower end of the lever and located in the path of movement of the bed.

8. In a press, the combination with a vertically movable cylinder, of a reciprocatory bed, and means for elevating the cylinder, said means including a movable yoke having its ends located in the path of movement of the bed.

9. In a press, the combination with a frame, of a vertically movable cylinder mounted on the frame, a reciprocatory bed, and means for elevating the cylinder, said means including a movable yoke mounted on the frame and movable longitudinally of the bed, said yoke having its ends extending across the ends of the bed and operated in opposite directions by the movement of said ends.

10. In a press, the combination with a supporting frame, of swinging levers mounted on the frame and having cam slots in their upper ends, a hanger frame having ends engaged in the slots, a cylinder journaled on the hanger frame, a reciprocatory bed mounted on the supporting-frame, and a yoke slidably mounted on the supporting frame and surrounding the bed, said yoke having link connections with the levers.

11. In a press, the combination with a vertically movable cylinder, of a gage vertically movable therewith, means for effecting the simultaneous movement of the cylinder and gage, and a bed coacting with the cylinder.

12. In a press, the combination with a feed table, of a cylinder located at one end thereof and movable in an upright direction, a gage movable with the cylinder, said gage being exposed when the cylinder is elevated and depressed when it is lowered and a bed coacting with the cylinder.

13. In a press, the combination with a cylinder-suspending frame movable in an upright direction, of a gage having a connection with the frame and elevated thereby, a cylinder journaled in the frame, and a bed coacting with the cylinder.

14. In a press, the combination with a cylinder-suspending frame movable in an upright direction, of a gage, a link connection between the gage and frame, a cylinder carried by the frame, and a bed coacting with the cylinder.

15. In a press, the combination with a feed

- table, of a vertically movable cylinder-suspending frame located at the end of the table, a carrier bar also arranged at the end of the table and having gage stops thereon, links connecting the ends of the carrier bar and the frame, a cylinder journaled in the frame, and a bed coacting with the cylinder.
16. In a press, the combination with a cylinder, of a bed coacting therewith, a feed table having its upper end disposed contiguous to the coacting portions of the bed and cylinder, and a guide strip extending from the table between the said bed and cylinder.
17. In a press, the combination with a cylinder, of a bed coacting therewith, a feed table having its delivery end disposed contiguous to the cylinder and at one side of the latter, a support located over the bed at the opposite side of the cylinder, and guide strips connecting the table and support and passing between said bed and cylinder.
18. In a press, the combination with a feed table, of a cylinder located at one end thereof, a bar arranged on the side of the cylinder opposite the feed table, a guide-strip extending from the table beneath the cylinder to the bar and a bed coacting with the cylinder.
19. In a press, the combination with a coacting bed and cylinder, of a guide strip extending between the same, and an endless tape passing between the bed and cylinder and coacting with the strip.
20. In a press, the combination with a coacting bed and cylinder, of a guide strip extending between the same, and a movable endless tape passing between the bed and cylinder and having an upper stretch located upon the strip and beneath the cylinder.
21. In a press, the combination with a coacting bed and cylinder, of supporting devices located on the opposite sides of the cylinder, a guide strip secured to the supporting devices and extending between the bed and cylinder, pulleys journaled on opposite sides of the cylinder contiguous to the strip, and an endless tape passing about the pulleys, one stretch of said tape being located beneath the strip, the other being located thereupon.
22. In a press, the combination with a cylinder, of supporting rods located on opposite sides of the cylinder, a strip secured to the rods and extending beneath the cylinder, an endless tape passing beneath the cylinder and on opposite sides of the strip and a bed coacting with the cylinder.
23. In a printing press, the combination with a cylinder, of a reciprocatory bed coacting with and movable beneath the cylinder, means for moving the bed, an oscillatory fly-frame having a pulley, an actuating device moved in opposite directions by the bed, and a cable wrapped upon the pulley of the fly-
- frame and having its ends connected to said device to rotate the pulley in reverse directions.
24. In a printing press, the combination with a cylinder, of a reciprocatory bed coacting with the cylinder, means for reciprocating the bed, a yoke surrounding the bed and having its ends located in the path of movement of the same, said yoke being moved in opposite directions by the bed, an oscillatory fly-frame, and a connection between the yoke and fly-frame whereby the latter is operated upon the movement of the former.
25. In a printing press, the combination with a feed table, of a reciprocatory bed operating beneath the same, a vertically movable revoluble cylinder, continuous guide strips extending from the table between the bed and cylinder and directing the paper from the table between said bed and cylinder, and means for automatically raising and lowering the cylinder to carry the same toward and from the guide strips.
26. In a press, the combination with a feed table, of a vertically movable revoluble cylinder arranged at one end thereof, a bed movable beneath the cylinder, guides extending from the table and interposed between the bed and cylinder, said guides being held against vertical movement with the latter, and means for automatically raising the cylinder away from and lowering it toward the guides at predetermined intervals.
27. In a printing press, the combination with a frame having spaced longitudinally disposed tracks, of a reciprocatory bed having on its under face, sets of spaced tracks, located respectively contiguous to its opposite sides, said tracks being disposed above and on opposite sides of the frame tracks, and a plurality of bearing wheels having their peripheries running on each frame track and journals running on the under sides of the spaced bed tracks, the upper portions of said wheels being located between said spaced tracks.
28. In a press, the combination with a reciprocatory bed, of a revoluble cylinder, and a cushion located on the bed and arranged to bear against the cylinder in advance of a form located on the bed.
29. In a press, the combination with a reciprocatory bed, of a revoluble cylinder, and a cushion adjustably mounted on the bed and arranged to bear against the cylinder in advance of a form located on the bed.
30. In a press, the combination with a reciprocatory bed, of a revoluble cylinder coacting therewith, guides interposed between the bed and cylinder, and a cushion arranged on the bed and adapted to bear against the cylinder in advance of a form located on the bed.
31. In a printing press, the combination with a cylinder, of a reciprocatory bed coacting with and movable beneath the cylinder, means for moving the bed, an oscillatory fly-frame having a pulley, an actuating device moved in opposite directions by the bed, and a cable wrapped upon the pulley of the fly-

with a bed, of a cylinder coacting therewith and movable toward and from the bed, means for thus moving the cylinder, guides interposed between the bed and cylinder, 5 and paper gages movable into and out of coaction with the cylinder, said gages coacting with said cylinder when the same is elevated.

In testimony, that I claim the foregoing as my own, I have hereto affixed my signature in the presence of two witnesses.

BENJAMIN WATTS MORGAN.
